UNITED STATES PATENT OFFICE.

WILLIAM W. WATSON, OF JAMESTOWN, NEW YORK.

SUSPENSION FOR FILING-DRAWERS.

1,144,670.

Specification of Letters Patent. Patented June 29, 1915.

Application filed December 23, 1914. Serial No. 878,631.

To all whom it may concern:

Be it known that I, WILLIAM W. WATSON, a citizen of the United States, residing at the city of Jamestown, in the county of Chautauqua and State of New York, have invented certain new and useful Improvements in Suspension for Filing-Drawers, of which the following, taken in connection with the accompanying drawings, is a specification.

The invention relates to supports for the drawers of filing cases, desks and similar constructions, and the object of the improvement is to provide a simple and durable form of telescoping suspension or supporting means for each side of the drawer whereby the drawers are held in horizontal position within the desk or filing case or in front of the same when withdrawn from the case, the outward movement of the drawer being limited yet sufficient to permit perfect freedom of access to all parts of the drawer when withdrawn; and the invention consists in the novel construction and combinations herein set forth and claimed.

In the drawings, Figure 1 is a crosswise sectional view of the drawer and the telescoping suspension on each side about midway of the length of the same showing the relation of the parts, the casing being shown in dotted line. Fig. 2 is a side elevation of a portion of the casing with the outer channel member of the suspension attached thereto and the inner channel member in the partially withdrawn position and the bar and rollers on the side of the drawer, the drawer being shown in dotted line. Fig. 3 is an elevation of the inner channel member of the suspension, the central portion being broken away. Fig. 4 is a side elevation of the drawer with the rollers attached thereto on a lengthwise bar. Fig. 5 is a lengthwise vertical sectional view of the outer channel member and an elevation of the inner channel member in position therein, the central portion of said channel members being broken away. Fig. 6 is a perspective view of the sheet metal and felt stop for the rear end of the outer channel member; and Fig. 7 is a perspective view of the rear end of said outer channel member into which said stop is inserted and attached. Fig. 8 is a perspective view of the rear end of the inner channel member showing the downwardly projecting portion of the same and the rollers revolvably mounted therein.

Like characters of reference refer to corresponding parts in the several views.

The numeral 10 designates the casing or desk side within which the drawer 11 is suspended.

The drawer 11 has the rollers 12 revolvably mounted on studs 13 upon the bar 14 attached lengthwise of each side of said drawer 11, the rollers 12 being attached to said studs a spaced distance from the bar 14. The rollers 12 are spaced also from one another and from each end of the drawer.

The numeral 15 designates the inner channel member of the suspension. The channel member 15 is made with a lengthwise central opening 16 formed between flanges on the upper and lower edges of the same. The upper flange is cut away at 17 to permit the insertion of the drawer rollers 12 into the member 15. The front end 18 is closed by turning the end of the sheet metal so as to fit within said upper and lower flanged edges and a felt stop 19 for the roller 12 is inserted within said closed end.

The rear end of the channel member 15 is formed by turning a rectangular shaped loop 20 in the sheet metal with an opening on its upper and lower sides, the sheet metal end being turned back upon itself and forming a firm stop against which the felt stop 21 is placed within the top and bottom flanges for the rollers 12 to bump against at said rear end. The wheels or rollers 22 are revolvably mounted in the looped portion 20 and project a portion of the wheel beyond the upper and lower edges, thereby forming roller bearing on both said upper and lower edges. The looped portion 20 projects below the lower edge of the channel portion of the member 15 to form a stop as well as a bearing.

The numeral 23 designates the outer channel shaped member of the suspension within which the inner channel member 15 is slidably mounted by means of the rollers 22 on the rear end of said inner channel member 15 and a roller 24 revolvably mounted in the lower portion of the front end of the channel member 23. Said roller 24 is proportioned as to the size of the projection of the loop portion 20 and roller 22 below the channel shaped portion of the member 15 so that said channel shaped portion of the member 15 will be held horizontally within the channel shaped member 23.

The rear end of the channel shaped mem-

ber 23 is closed by means of a felt stop 25 which fits tightly in a channel or U-shaped piece 26. The piece 26 fits closely within the rear end of the channel member 23 and 5 is preferably attached thereto after insertion by means of acetylene welding. The front portion of the upper flange of the channel member 23 is cut-away to allow admission of the rear end 20 of the channel 10 member 15 behind the roller 24.

A stop 27 is provided for the inner member 15 a spaced distance from the outer end of the channel member 23, said stop 27 is constructed like the rear stop 25 and 26 15 with a felt insert in a U-shaped piece, a threaded hole being provided through said U-shaped piece and the lower flange of the channel member 23 into which a screw is inserted after the insertion of the rear end 20 of the inner channel member 15, thereby uniting the parts so that they cannot be taken apart except by the removal of the screw in the stop 27. The removal of said screw permits the stop 27 to slide forward against 25 the roller 24, thereby permitting the rear end 20 to be removed through the open front end of the channel member 23 and the reinsertion of said channel member for reassembling. The stop 27 is slipped up to its 30 place and the screw inserted making a simple reassembling construction for said parts. The downward projection of the loop 20 forms a firm stop on the rear end of the channel member 15 to strike against the 35 felted stop 27 when the drawer 11 is drawn forward to limit its withdrawal in front of the case.

It is apparent that this makes an exceedingly strong suspension construction which 40 may be easily attached to the drawer and to the case at each side of the drawer, occupying small space; that the drawer is readily removable from the suspension and returnable thereto; and that all the parts may be 45 struck up at low cost to the manufacturer.

It is obvious also that the rollers are so mounted that they cannot get out of position and yet invariably support the drawer no. 50 matter how heavily loaded so that it runs freely and easily.

I claim as new:

1. In a suspension for drawers the combination with a casing of, outer channel shaped suspension members on the inner 55 walls of said casing, a stop in the rear end of said channel shaped members, inner channel shaped members slidably mounted within each of said outer channel shaped members and opening inwardly, the rear end

of each of said inner channel members 60 formed in a loop and projecting below the channel portion of said member to form a stop, rollers revolvably mounted in said loop projecting above and below the same to fit against the walls of said outer channel 65 shaped member and form roller bearings, a stop within each of said outer channel shaped members a spaced distance from the outer end to engage the downward projection of said loop and limit the outward 70 movement of the drawer, a drawer fitting between said suspension members, rollers revolvably mounted on studs a spaced distance from the outer sides of said drawer to engage within said inner channel shaped 75 members, said inner and outer channel shaped members having openings in the flanges thereof to receive said rollers on said drawer and to permit removal of the same. 80

2. In a suspension for drawers the combination with a casing of, outer channel shaped suspension members on the inner walls of said casing and a felt stop in the rear end of each of said channel shaped 85 members, smaller channel shaped members slidably mounted one within each of said outer channel shaped members and opening inwardly, the rear end of each of said inner channel members formed in a return bend 90 loop and projecting below the lower edge of the channel portion of said inner member to form a stop, rollers revolvably mounted in the upper and lower ends of said loop to form roller bearings against the inner 95 walls of said outer channel member, a felt stop removably attached within the lower flange of each of said outer channel members a spaced distance from the front end to engage said stop at the rear end of said 100 smaller channel member and limit the outward movement of the drawer, a bar lengthwise of each of the outer sides of said drawer, studs on said bars a spaced distance apart, rollers revolvably mounted on said 105 studs a spaced distance from the sides of the drawer to engage within said inner channel members, said inner and outer channel members having openings in their upper flanges to permit the ingress and egress of said rollers on said drawer. 110

In testimony whereof I have affixed my signature in the presence of two witnesses.

WILLIAM W. WATSON.
